UNITED STATES PATENT OFFICE.

WILLIAM H. AYER, OF CLAREMONT, NEW HAMPSHIRE.

PICKER-CHECK FOR LOOMS.

No. 861,013.

Specification of Letters Patent.

Patented July 23, 1907.

Application filed September 4, 1906. Serial No. 333,127.

To all whom it may concern:

Be it known that I, WILLIAM H. AYER, a citizen of the United States, residing at Claremont, in the county of Sullivan and State of New Hampshire, have invented 5 certain new and useful Improvements in Picker-Checks for Looms, of which the following is a specification, reference being had therein to the accompanying drawings.

My invention relates to improvements in shuttle 10 checks for looms, and has for its object to provide a yielding buffer to stop the flight of the shuttle, which by slight changes may be applied to any "drop box" loom now in ordinary use.

Another object of my invention, is the provision of a 15 shuttle check which will yield quickly to the impact of the shuttle, on the picker but which will return more slowly to its normal position, so that it will not cause the shuttle to rebound.

The invention also has for its object, to provide a 20 yielding impact band which may be quickly and readily adjusted both as to tension, and as to location with regard to the shuttle guides.

With these and other objects in view, my invention 25 consists of a yielding impact band, a stationary and an adjustable post over which the impact band is adapted to move, and a pair of adjustable coil springs, the ends of the impact band being secured to said springs.

Other novel and useful features of construction, combination and arrangement of parts will become apparent 30 from the following description taken in connection with the drawings.

Figure 1, is a plan view of my improved shuttle check as applied to an ordinary shuttle box guide. Fig. 2, is a front end view thereof looking toward the 35 right of Fig. 1. Fig. 3, is a rear end elevation of the same. Fig. 4, is a detail sectional view of one of the coil springs and the spool upon which it is mounted. Fig. 5, is a similar view of a slightly modified form of coil spring and support therefor.

40 In the drawings: the numeral 1, designates the shuttle box guide of an ordinary loom provided with the usual guiding flanges 2. Secured to the frame of the box guide by means of the bolt 3, is a base plate 4, preferably formed with an extension 5, to engage the side 45 face of the guiding flange and prevent lateral movement of the base plate.

At the lower end of the base plate, at a point some distance below the passage between the guiding flanges, is provided a post or lug 6, which is preferably formed integral with the plate. This post is practically semi-circular in shape so as to provide an outer curved wearing surface. Adjustably fixed to the upper end of the base plate, upon the adjustable securing bolt 7, is an eccentric roller 8, and passing over said roller and the

post at the opposite end of the plate, is an impact band 55 9, of leather or other suitable material. Upon the impact band, opposite the opening between the guiding flanges, is secured by means of fastenings 10, a metal re-inforcing strip or plate 11, adapted to receive the impact of the shuttle on the picker.

60 Mounted in the base plate in the rear of the impact band are a pair of bolts 12, provided with securing nuts 13. Upon said bolts are mounted the spools 14, arranged one above the other and provided with an outer retaining flange 15. Coil springs 16, are wound upon 65 the spools and to the hooked ends 17, of the springs, are secured the free ends of the impact band. The bolts 12, are each provided with a narrow or elongated head 18, which engages a slot or cut-away portion 19, formed in the center of the transverse ridge 20, on the head of 70 the spool, so that the spool is thereby held against rotation on the bolt. The inner ends of the springs are anchored in the spools (shown in dotted lines Fig. 4) and as the outer or free ends, are secured to the impact band, the tension of the impact band may easily be regulated 75 by loosening the nuts on the bolts 12, and rotating the bolts until the springs bring the impact band to the proper tension.

To prevent rapid wear of the spring coil, I may use a slightly modified form of support for the coil, as shown 80 in Fig. 5. In this instance, the supporting roller and securing bolt are the same as before, but between the outer coil spring 21, and the stationary spool 22, is interposed a wire coil 23, which is loosely mounted upon the spool. This wire coil 23, moves with the coil spring 85 and thus prevents undue friction of the parts, and allows access of oil to the adjusting roll.

To adjust the shuttle check to looms of various makes, it may be necessary to move the impact band toward or away from the guiding flanges. This is done by 90 loosening the eccentric roller which supports one end of the impact band, and rotating said roller until the band occupies the proper position. The tension of the band is readily altered by rotating the adjustable rolls carrying the coil springs. By placing the spring rolls 95 in rear of the impact band and located above the point of impact on the band, a perfectly clear space is left between the two parallel sides of the band, so as to allow great freedom in the movement of the band, a point which is readily appreciable. As described, it will be 100 observed that the impact band is supported upon and passes over two posts with which it has frictional contact, and as with every impact it slides over both of the posts, double frictional contact surface is provided, and the band is greatly retarded in its return movement 105 after the impact.

From the foregoing description taken in connection with the drawings, it will be evident that I have pro-

vided a simple, practical and inexpensive construction of shuttle check, which is entirely efficient and practical, and accomplishes all the objects herein set forth.

I claim:

- 5 1. A shuttle check comprising an impact band passing over a fixed and an eccentrically mounted frictional support the last named support for purpose of adjustment, a pair of independent springs mounted outside the band adjacent thereto, the free ends of the band each secured to one of said springs.
- 10 2. A shuttle check comprising a band having a hard impact surface, a fixed and an adjustable frictional support for the band, independent tension springs for each free end of the band and spools located adjacent the outside of the band forming supports for the springs.
- 15 3. In a shuttle check, the combination with a fixed and a relatively adjustable support, an impact band passing over said supports, of adjustable independent tension means for the free ends of the band said means comprising coiled springs mounted upon spools, the spools being rotatably adjustable to vary the tension.

4. In a shuttle check, the combination with a base plate and guiding flanges, of spools, adjustably secured to the base plate, spiral springs confined upon said spools, a fixed and an adjustable support on the base plate adjacent the 25 guiding flanges, an impact band passing over the supports, the ends of the band being brought together and each end secured to one of the springs.

5. In a shuttle check, the combination with a base plate and impact band mounted thereon, supporting spools adjustably secured to the base plate, coil springs confined on each of the spools and each having one end anchored to the spool, the free ends of the springs being engaged by the ends of the impact band, and loose bearing coils interposed between the spools and the coils thereon to reduce the friction of the parts.

In testimony whereof I affix my signature in presence of two witnesses.

WILLIAM H. AYER.
